UNITED STATES PATENT OFFICE.

WALTER KEHSE, OF DRESDEN-KEMNITZ, GERMANY.

WINDING APPARATUS FOR THE MANUFACTURE OF INSULATING TUBES CONSISTING OF PAPER AND RESIN.

Application filed September 5, 1924. Serial No. 736,025.

To all whom it may concern:

Be it known that I, WALTER KEHSE, chief engineer, a subject of the Free State of Prussia, German Republic, and resident of Dresden-Kemnitz, German Republic, have invented a new and useful Winding Apparatus for the Manufacture of Insulating Tubes Consisting of Paper and Resin, of which the following is a specification.

10 The manufacture of insulating tubes consisting of paper and resin offers difficulties in certain directions, partly found in the kind of paper used and partly in the working itself. For said working it is necessary to bring the paper-layers into such an intimate contact with each other that, after the hardening procedure, intervals are avoided between the layers. For obtaining said purpose, the paper-strip or band must 15 be under high tension and the winding-core or drum is pressed against the heating cylinders by brake-tension. According to a modification the winding-core or drum is pressed against said heating cylinders by 20 weighted rollers or spring-tension. However, if said means are to be of high effect, the pressures must be highly intense and require inconvenient dimensions of the weight- 25 rollers, or necessitate complicated wind- 30 lasses in case it is intended to obtain the pressure by screws and springs. It is of utmost importance that the pressure acts in full intensity immediately on attaching the paper, as else the interior layers are 35 wound without any sufficient pressing effect. In view of the fact that the paper never runs smoothly knots and folds must be pressed down in any case, a fact which can not be obtained with the means used 40 up to now.

The present invention has for its object to overcome said drawbacks. For this purpose hydraulic presses alone or in combination with accumulators are used. By said 45 hydraulic presses and accumulators pressures suitable to attach the paper can be obtained, which would involve very inconvenient dimensions when loads produced by weights or springs are used. If accumula- 50 tors are used the pressure for attaching the paper is immediately present in its full intensity. It has been experienced that even for tubes of larger dimensions and with the use of a pressure of 20,000 kilograms essen- 55 tially denser or tighter tubes are obtained

than those manufactured according to the procedures in use up to now. A proof of this fact is that the specific weight is higher and the structure of the paper is much more dense. Indeed the advantage mentioned is 60 found in the fact that the paper is perfectly impregnated with the heated resin when using the high pressure, whereas with the processes used up to the present it was necessary to make use of sized paper. In case of 65 winding off the tubes produced in the known manner the layers of paper and resin could still be discovered.

In the drawing:

Fig. 1 is a sectional elevation illustrating 70 an apparatus embodying my present invention.

Fig. 2 is a similar view showing another form of the invention, and

Fig. 3 is also a sectional elevation showing 75 a third form of the invention.

a is the winding-core or cylinder driven in any suitable manner and resting on two cylinders *b*, the interior chambers of which are heated by gas or electricity. The shafts 80 or trunnions of said heating cylinders are arranged in ball bearings (not shown) so as to be easily rotated and can be adjusted or displaced lengthwise.

c are two pillow-blocks carrying the heating cylinders *b* and arranged to be adjusted by screw-bolts *d* according to the different diameters of the insulating tubes to be manufactured on the winding cores *a*. *e* is the insulating-tube formed by a paper- 85 band surrounding at first only a small part of the periphery of the winding-core *a* and supplied by a cylinder not shown in the drawing. Said insulating-tube is produced by corresponding turns or layers of 90 the paper round the core *a*. *f* is a shaft passed through the winding-core and carrying on both its ends two ball-bearings *g* enclosed into a suitable casing to which a connecting-bar *h* is fastened. A casing 100 containing a strong coiled spring may be inserted into said connecting-bar. The lower end of said connecting-bar is connected by a trunnion *i* with the lever *j* which is movable on the trunnion *k* and connected 105 by a bolt *l* with a bar *m*, forming part of a hydraulic press. *n* is the piston movable within the cylinder *o* of the press.

Said hydraulic press and the connecting-bars moved by its piston are duplicated so 110

that the winding-core *a* is uniformly pressed down against the heating cylinders *b*.

By corresponding dimensions of the 5 tons *n* the pressures exerted against the winding-core may be varied within wide limits, so that the paper-tubes can be manufactured with more or less density.

In the arrangement shown in Fig. 2 corresponding in its upper part to the arrangement shown in Fig. 1, the connecting-bar *h* is directly connected to the piston *n* of the hydraulic cylinder *o*. The interior of the latter is divided by the piston *n* into 10 two compartments. A rod *p* arranged below the piston *n* is suitably guided and is moved to and fro within a prolonged part of the lower cylinder-casing. The upper interior part of said casing is connected by 15 a tube *q* with a valve-casing *s*, whereas the interior of the lower prolonged part of said hydraulic press is connected by a tube *r* to a pipe *t* connected with an accumulator not shown in the drawing. By a respective 20 position of the valve arranged within the casing *s* the piston *n* is moved in a downward and upward direction, whereby the winding-core *a* is correspondingly pressed against the heating-cylinders *b* or released 25 from them. The action of the modified arrangement shown in Fig. 2 is the same as that shown in Fig. 1.

In another modification shown in Fig. 3 the piston *n* is arranged above the winding-core *a* resting on the heating-cylinders *b*, *b* and the piston *n* is connected by rods *h* with a pressure-cylinder *u* running in ball-bearings. In this arrangement the winding-core rotates between the heating-cylinders 30 *b*, *b* and the pressure cylinder *u*.

What I claim is:

1. In an apparatus for winding paper tubes comprising spaced heated cylinders, a winding core, and hydraulically operated devices for moving the winding core toward the heated cylinders and pressing the paper as wound on the core against the said heated cylinders and between the same and the winding core.
2. An apparatus for winding paper tubes comprising spaced heated cylinders, a wind-

ing core, and hydraulically operated devices for moving the said winding core toward and away from the said heated cylinders, whereby when moved toward the heated cylinders the winding core is pressed against the same with the paper web intervening.

3. An apparatus for winding paper tubes comprising spaced heated cylinders, a winding core, means for shifting the heated cylinders relatively to the winding core, and hydraulically operated devices for moving the winding core toward the heated cylinders and pressing the paper as wound on the core against the said heated cylinders and between the same and the winding core.

4. An apparatus for winding paper tubes comprising heated cylinders, a winding core, means for shifting the heated cylinders toward and away from each other to adjust their positions relative to each other and to the winding core, and hydraulically operated devices for moving the said winding core toward and away from the said heated cylinders, whereby when moved toward the heated cylinders the winding core is pressed against the same with the paper web intervening.

5. An apparatus for winding paper tubes comprising heated cylinders, a block upon which each heated cylinder is revolubly mounted, means for moving the blocks toward and away from each other to shift the relative positions of the said heated cylinders, a winding core, and hydraulically operated devices for moving the said winding core toward and away from the said heated cylinders, whereby when moved toward the cylinders the winding core is pressed against the intervening paper as the same is wound on the core, and when moved away from the heated cylinders, the space between the same and the core is sufficient to remove the tube from the core and to prepare the core for winding the next tube.

In testimony, that I claim the foregoing as my invention, I have signed my name this twenty-first day of August, 1924.

WALTER KEHSE.
